UNITED STATES PATENT OFFICE

172,465

AERIAL TARGET

Bruce E. Del Mar, Los Angeles, Calif., assignor to
Del Mar Engineering Laboratories, Inc., Los
Angeles, Calif., a corporation

Application August 16, 1952, Serial No. 21,070

Term of patent 14 years

(Cl. D71—1)

To all whom it may concern:

Be it known that I, Bruce E. Del Mar, a citizen of the United States and a resident of Los Angeles, in the county of Los Angeles and State of California, have invented a new, original, and ornamental Design for an Aerial Target, of which the following is a specification, reference being had to the accompanying drawing, forming a part thereof.

Figure 1 is a perspective view of an aerial target, showing my new design;

Figure 2 is a top plan view;

Figure 3 is a front elevational view; and
Figure 4 is a side elevational view.

I claim:

The ornamental design for an aerial target, substantially as shown.
